SHOW CAGE FOR BIRDS

Bryan W. Womack, Fort Worth, Tex.

Application July 17, 1953, Serial No. 26,033

Term of patent 14 years

(Cl. D31—2)

To all whom it may concern:

Be it known that I, Bryan W. Womack, have invented a new, original, and ornamental Design for a Show Cage for Birds, of which the following is a specification, reference being had to the accompanying drawing, forming a part hereof.

Figure 1 is a front perspective view of a show cage for birds showing my new design, the front and side slideable panels being shown in closed position.

Figure 2 is a front perspective view thereof, the side panel being shown raised, and the front panel removed.

Figure 3 is a rear perspective view thereof, with the panels arranged as in Figure 1.

Figure 4 is a rear perspective view thereof with the removable front panel being shown in place at the rear of the cage as in Figure 2.

I claim:

The ornamental design for a show cage for birds, substantially as shown.

BRYAN W. WOMACK.
